Inventor:

Fred S. Carr,
by Emery Booth, James V. Verry
Attest,

UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

Application filed March 8, 1921. Serial No. 450,746.

To all whom it may concern:

Be it known that I, FRED S. CARR, a citizen of the United States, and a resident of Newton, in the county of Middlesex and 5 Commonwealth of Massachusetts, have invented an Improvement in Fasteners, of which the following description, in connection with the accompanying drawings, is a specification, like characters on the drawings representing like parts.

This invention pertains to improvements in separable fasteners. It is among the objects of the invention to provide a fastener of simple and rugged construction and 15 which provides satisfactory holding power.

In the drawings, which show a preferred form of one illustrative embodiment of my invention:—

Figure 1 is an elevation of the stud and 20 socket of a fastener, the stud and socket being carried by their respective fabrics;

Fig. 2 is a section on the line 2—2 of Fig. 1; and

Figs. 3 and 4 are plan views of the preferred forms of stud and socket secured to 25 their carrying fabric.

Referring to the drawings, and to the preferred form of my invention selected for 30 illustrative purposes, I have shown a stud which may be of usual construction and includes a head 5, neck 6 and base flange 7, 35 stitched to the stud carrying fabric 8. Co-operating with this stud I have shown a socket 9, which in the preferred form of my invention is made from a single piece of sheet metal having a stud-receiving aperture 10 therein and which is slotted at one side to 40 permit resilient expansion of the sheet metal to enlarge the stud-receiving aperture for passage of the head of the stud therethrough. I preferably, as illustrated, 45 provide means for limiting the resilient expansion of the spring, and in the embodiment of my invention illustrated I effect this by 50 making the slot in the socket present opposed faces 11 and 12 having a space 13 between them, the extent of this space limiting the resilient expansion of the sheet metal to 55 enlarge the stud-receiving aperture. These faces 11 and 12 may conveniently be formed by making the slot crooked and I have found that the Z-shaped slot illustrated performs this function satisfactorily, the central portion of the Z being preferably, as illustrated, 60 wider than the end portions thereof. Where

my invention is used with the one-piece socket as illustrated, the spring portion being in fact the entire socket, I may provide stitch-receiving apertures 15, 16 and 17 through the socket, these stitch-receiving 60 apertures preferably being arranged about the stud-receiving aperture on those sides thereof which are out of the direct line of strain between stud and socket when in use, that side of the socket presenting the slot 65 preferably being arranged toward the line of strain and the stitch-receiving apertures preferably being three in number and symmetrically disposed about the other three sides of the stud-receiving aperture or opening. 70

The holding power of the fastener under lateral strain may, if desired, be increased by providing a notch 18 in the sheet metal spring, preferably on that side thereof toward the slot therein which extends from the stud-receiving aperture to the periphery of the socket. The resiliency of the socket may be increased by slotting the metal between the stud-receiving aperture and the stitch-receiving apertures, these slots being numbered 20 on the drawing. 80

When the stud and socket are attached to their respective fabrics and when these fabrics are pulled apart in such a way as to 85 produce lateral strain between stud and socket in the direction of the arrow in Fig. 3 of the drawings, the strain may be so great as to enlarge somewhat the stud-receiving aperture, but this cannot be enlarged beyond a predetermined amount because of the limiting means limiting this expansion, and the expansion will not be sufficient to permit the head of the stud to tip out of the stud-receiving opening in the socket, especially 90 where a notch is provided permitting limited lateral displacement of the stud in a direction toward the slit in the socket. The notch 18 is, however, not sufficiently great to interfere with ready separation of the stud from 95 the socket when separating force is applied between the engaged parts at an angle greater than that which is likely to be produced by the resolution of forces arising from lateral strain between stud and socket. 100

While I have shown and described a preferred form of one embodiment of my invention, it will be understood that changes involving omission, substitutions, alteration and reversal of parts, and even changes in 110

the mode of operation, may be made without departing from the scope of my invention, which is best defined in the following claims.

5. Claims:

1. A socket for a separable fastener, comprising a resilient element having a stud-receiving aperture therein, said resilient element discontinuous at one side to permit 10 resilient enlargement of the stud-receiving aperture, and said resilient element providing interlocking parts limiting the extent of enlargement of the stud-receiving aperture.
2. A socket for a separable fastener including a spring formed of sheet metal having a stud-receiving aperture therein, said spring slotted at one side, the slot being crooked to provide faces which engage to limit the extent of spreading of the spring 15 when under strain.
3. A socket for separable fasteners formed of a single piece of sheet metal having a stud-receiving aperture therein, said sheet metal slotted at one side from its periphery 20 to the aperture therein, the slot presenting opposed faces having a space between them, the extent of such space limiting resilient expansion of the sheet metal to enlarge the stud-receiving aperture.
4. A single piece socket for separable fasteners presenting a stud-receiving aperture, said socket resilient to permit expansion of the aperture to a predetermined limit opposed by the resiliency of the socket only, 25 and said socket presenting limiting means for opposing further expansion of the aperture when the predetermined limit has been reached.
5. A single piece sheet metal socket for separable fasteners presenting a stud-receiving aperture, said socket resilient to permit expansion of the aperture to a predetermined limit opposed by the resiliency of the socket only, and said socket presenting limiting means for opposing further expansion of the aperture when the predetermined limit has been reached. 30
6. A sheet metal spring for a separable fastener presenting a stud-receiving aperture and having a slot extending from said aperture to the periphery of the spring, said slot presenting walls having portions 35 therein, said portions spaced apart, the spacing therebetween determining the limit of free expansibility of the spring.
7. A sheet metal spring for a separable fastener presenting a stud-receiving aperture and having a slot extending from said aperture to the periphery of the spring, said slot Z-shaped and wider at the central portion of the Z than at the end portions thereof. 60
8. A socket for separable fasteners including a resilient part having a stud-receiving aperture therethrough, and a slit or slot 65 from the aperture to the periphery of the resilient part, said slit or slot Z-shaped and permitting while limiting expansion of said resilient part.
9. A socket for separable fasteners comprising a sheet metal piece having a stud-receiving aperture therethrough, stitch-receiving apertures therethrough and a slit extending from said aperture to the periphery of the piece at one side, said slot crooked to 70 provide surfaces limiting expansion of said stud-receiving aperture. 75
10. A socket for separable fasteners comprising a sheet metal piece having a stud-receiving aperture therethrough, stitch-receiving apertures therethrough and a slit extending from said aperture to the periphery of the piece at one side of said aperture, said slot crooked to provide surfaces limiting expansion of said stud-receiving aperture, and said stitch-receiving apertures grouped about the other three sides of said stud-receiving aperture. 80
11. A socket for separable fasteners comprising a sheet metal piece having a stud-receiving aperture therethrough, stitch-receiving apertures therethrough and a slit extending from said aperture to the periphery of the piece at one side of said aperture, said slot crooked to provide surfaces limiting expansion of said stud-receiving aperture, said piece slotted between said stud-receiving aperture and a plurality of said stitch-receiving apertures. 90
12. A socket for a separable fastener including a sheet metal spring presenting a stud-receiving aperture and having a slot extending from said aperture to the periphery of the spring, stitch-receiving apertures through said spring and limiting means for 95 determining the limit of free expansibility of said spring. 100

In testimony whereof, I have signed my name to this specification.

FRED S. CARR
